(57) CLAIM

The ornamental design for a display screen or a portion thereof with a graphical user interface, as shown and described herein.

DESCRIPTION

The file of this patent contains at least one drawing/photograph executed in color. Copies of this patent with color drawing(s)/photograph(s) will be provided by the Office upon request and payment of the necessary fee.

This application is related to the following commonly owned co-pending patent applications: U.S. application Ser. No. 29/865,394, entitled “Display Screen or Portion Thereof

With a Graphical User Interface,” U.S. application Ser. No. 29/865,395, entitled “Display Screen or Portion Thereof With a Graphical User Interface,” U.S. application Ser. No. 29/865,397, entitled “Display Screen or Portion Thereof With a Graphical User Interface,” U.S. application Ser. No. 29/865,399, entitled “Display Screen or Portion Thereof With a Graphical User Interface,” U.S. application Ser. No. 29/865,400, entitled “Display Screen or Portion Thereof With a Graphical User Interface,” U.S. application Ser. No. 29/865,401, entitled “Display Screen or Portion Thereof With a Graphical User Interface,” U.S. application Ser. No. 29/865,402, entitled “Display Screen or Portion Thereof With a Graphical User Interface,” U.S. application Ser. No. 29/865,403, entitled “Display Screen or Portion Thereof With a Graphical User Interface,” U.S. application Ser. No. 29/865,405, entitled “Display Screen or Portion Thereof With a Graphical User Interface,” and U.S. application Ser. No. 29/865,406, entitled “Display Screen or Portion Thereof With a Graphical User Interface”.

The FIGURE is a front view of a display screen or portion thereof with a graphical user interface of our new design. The outer perimeter broken lines in the drawing represents a display screen or portion thereof and forms no part of the claimed design. The remaining broken lines in the drawing illustrate portions of a graphical user interface that forms no part of the claimed design.
